CLAIM

The ornamental design for a portable pool cleaner, as shown and described.

DESCRIPTION

FIG. 1 is a front view of a portable pool cleaner showing my new design;

FIG. 2 is a rear view thereof;

FIG. 3 is a left side view thereof;

FIG. 4 is a right side view thereof;

FIG. 5 is a top view thereof; and,

FIG. 6 is a perspective view thereof.

The dash lines included depict the environment and are not part of the claimed design.
